ATMOSPHERIC AIR**

(76) Inventor: **Elias V. Coe**

Elias. V. Cox. Warwick, R. I.

Letter Patent

The Schedule referred to in this Letter Patent and making part of the same containing a description in the words of the said Elias Cox, of his improvement in the art of Churning.

It is declared that this Patent shall come into force on the day that Elias V. Cox, Warwick in the County of Orange and State of New York have invented a new and useful improvement in the art of Churning Milk or Cream and that the following is a full and exact description of the said art of Churning as invented or applied by me, which consists in the application or forcing air into Milk or Cream by means of an air or forcing pump, bellows or other like Machinery or Instrument - provided of hand holes, sight, steam, wind, animal or any other power.
